UNITED STATES PATENT OFFICE.

CHARLES B. GUDEBROD, OF ST. DAVIDS, PENNSYLVANIA, ASSIGNOR TO GUDEBROD BROS. SILK CO., INC., OF NEW YORK, N. Y., A CORPORATION OF NEW YORK.

METHOD OF FORMING THREAD TIPS.

Application filed June 23, 1923. Serial No. 647,343.

To all whom it may concern:

Be it known that CHARLES B. GUDEBROD, a citizen of the United States, residing at St. Davids, in the county of Delaware and

5 State of Pennsylvania, has invented certain new and useful Improvements in Methods of Forming Thread Tips, of which the following is a specification.

This invention relates to improvements in 10 the method of manufacturing silk, cotton or linen thread used for stringing beads and the like, and more especially to the preparation of the end or ends of the threads so that the same will easily pass through the openings through the beads, thereby doing away 15 with necessity of using a needle.

An object of the invention is to provide a suitable silk, cotton or linen thread, which will preferably be formed from three separate cords which will be twisted together 20 and cut into the desired length according to the length that the string of beads is to be, and then treat the ends thereof with a material which will harden the same, so that 25 they will freely and easily pass through the openings in the beads.

A further object of the invention is to provide a suitable thread of silk, cotton or linen, which may be made from one or more 30 threads, and which will have its ends dipped in a bath of hot bone glue, after which in a light solution of bees' wax, which will make the same sufficiently stiff for easily 35 passing through the openings in the beads to be strung, though not so stiff that the ends will split or crack.

Other objects will appear as the description proceeds.

In the accompanying drawings which 40 form a part of this application—

Figure 1 is a side elevation of a thread used for threading beads, showing one end of the same prepared in accordance with my improved method;

45 Figure 2 is a front elevation of the improved tip portion as coated with bone glue, and

Figure 3 is a front elevation of the tip completed with a coating of bone glue, and 50 also a coating of bees' wax.

Like characters of reference are used throughout the several views and the accompanying drawings to designate corresponding parts.

In carrying out my invention, I employ 55 a thread 1 made from silk, cotton or linen, which may be composed of one or more cords as indicated by 2.

These cords 2 are spun and twisted together, and are cut the desired length, according to the length of the string of beads, after which the ends 3 are immersed in a bath of hot bone glue, which will tend to harden the said ends to a certain degree, so that they can be used in the manner of a 60 needle for threading the beads 4 on the thread. The ends 3 will then be quite stiff, but will be somewhat pliable so that the same will not readily crack or split.

After the hardening process has been applied to the ends 3 of the string 1, they will be immersed in a light solution of bees' wax, which when the ends of the thread are passed through the openings in the beads, will tend to fill the crevices on the edges of 75 the beads, thereby doing away to a great extent with the usual chafing or cutting of the string by the beads. It will therefore be apparent that the life of the string will be very much longer than the ordinary 80 string used for this purpose.

The old method of stringing beads is to take a fine needle and threading the same with a fine thread so that the needle and thread may be passed through the openings in the 85 beads. This method is obviously inefficient, since a small thread only can be used, while in my improved method, the maximum size of thread may be utilized thereby providing for the greatest possible life and efficiency 90 of the thread.

Many minor changes may be resorted to without departure from the spirit of the invention.

Having thus described my invention, what 95 I claim as new and desire to secure by Letters Patent of the United States, is:

1. The method of forming a tip on a thread for use in stringing beads, consisting of immersing the ends of the thread in hot 100

bone glue, after which the said ends are again immersed in a light solution of bees' wax.

2. The method of forming a tip on a thread for use in stringing beads, consisting in twisting one or more cords of silk, cotton or linen together, cutting the same in the

desired length, immersing the ends thereof in a solution of hot bone glue, and finally immersing the said ends in a light solution 10 of bees' wax.

In testimony whereof I affix my signature.

CHARLES B. GUDEBROD.
